R. T. HORTON

FIRING DOOR

Filed Feb. 18, 1927

UNITED STATES PATENT OFFICE.

ROBERT T. HORTON, OF GREENWOOD, INDIANA.

FIRING DOOR.

Application filed February 18, 1927. Serial No. 169,302.

This invention relates to furnace fire box doors and pertains particularly to a swinging door having a foot control operating means.

5 The door embodying this invention is intended for stationary boilers or locomotives of all descriptions as well as for furnaces for house heating purposes, and is designed to be used as a right or left hand operated door. The use of a door of this type is calculated to save much fuel and owing to the location of the supporting pivot on the plummet line (on a line running along the rear edge of the furnace door opening) the 10 door is extremely easy to operate.

The primary object of this invention is to provide, in a manner as hereinafter set forth, a door structure for a furnace fire box so mounted before the fire box opening that 15 the opening of the door may be accomplished by the depression of a lever operating button in the floor before the furnace. By this means the furnace door may be swung to open position through the manipulation of 20 the operating mechanism by the foot, leaving the operator's hands free for the handling of the coal shovel. Upon release of the foot control mechanism, the door is designed to drop back to place through gravity.

25 Another object of the invention is to provide, in a manner as hereinafter set forth, in connection with a swinging furnace door of the character described, a guide track which will control the free end of the door in any 30 position to which it moves so that the door will at all times be maintained in relatively close relation to the front of the furnace structure and will be properly guided back to a closing position upon release of the control mechanism.

35 Other objects and advantages of the structure embodying this invention will become apparent as the description of the same proceeds and the invention will be best understood from a consideration of the following 40 detailed description taken in connection with the accompanying drawings forming a part of this specification, with the understanding however, that the invention is not confined 45 to any strict conformity with the showing of the drawings but may be changed or modified so long as such changes or modifications mark no material departure from the salient features of the invention as expressed in the 50 appended claim.

In the drawings:

Figure 1 shows a furnace structure and door associated therewith, in front elevation, a portion of the floor being shown in section to show a part of the foot control mechanism 60 lying therebeneath, and

Figure 2 is a sectional view taken transversely through the door and adjacent furnace structure showing the control lever.

Figure 3 is a section taken upon the line 65 3—3 of Figure 1.

Referring now to the drawing in detail wherein like numerals of reference indicate corresponding parts throughout the several views, the numeral 1 indicates a portion of 70 the front of a furnace structure, the floor upon which the furnace is supported being indicated by the numeral 2. A fire box opening 3 is shown over which lies the closure structure or door indicated generally 75 by the numeral 4.

Extending upwardly from the top edge of the door at the rear end thereof is a supporting arm 5 which at the upper portion of the rear edge thereof is made materially 80 thinner to form the apertured ear 6. The longitudinal center or plummet line of the arm 5 is substantially in alignment with the rear edge of the door opening 3 as is shown and upon this plummet line, intermediate the 85 ends of the arm, an aperture is formed for the reception of a supporting pivot pin 7. As before pointed out, this location of the pivot pin 7 assists materially in easing the 90 opening operation of the door.

Overlying the major portion of the arm 5 is a hood structure of segmental form, as indicated at 8 and formed about the outer curved edge of this hood are laterally directed fingers 9 which are secured to the 95 face of the furnace structure and maintain the hood proper in spaced relation to the face of the furnace. The pin 7 has its inner end journaled into the front wall of the furnace while the outer end thereof extends 100 through the arm 5 and the hood body 8 as is clearly shown in Figure 1, thus the pin is supported at each end and undue strain thereon is prevented.

Secured to the face of the furnace 1 adjacent the lower end of the rear edge of the door 4 is a stop member 10 which, as will be readily understood, limits the downward swinging movement of the door maintaining it in horizontal position transverse- 110

ly of the face of the furnace across the opening 3.

The bottom front corner 11 of the door 4 engages under the raised inner or concave edge of an arcuate guide track 12, which track is secured to the face of the furnace adjacent the free or swinging edge of the door as shown in Figure 1.

The guide track 12 is of arcuate contour 10 as will be readily understood, the arc of the track being struck from the pivot point 7 of the door so that the finger 11 will be always engaged by the track during the opening of the door as above described.

15 This track member comprises two portions 13 and 14 which are arranged in offset parallel relation, the portion 14 being secured to the face of the furnace, thus maintaining the portion 13 in spaced relation with respect to the furnace face as shown.

The top edge of the door 4 has mounted thereon, an eye member 15 which is adapted to be engaged by a hook 16, which is pivotally attached to the face of the furnace 25 structure, when the door is in raised position to hold the same open when desired.

Pivots connected to and extending downwardly from the apertured ear 6 at an inclination with respect to the rear end 30 edge of the door is a two part pull arm 17, a turn buckle 18 connecting the parts together for the proper adjustment of the arm. As shown the upper end of the arm attaches to the ear in a plane above the pivot 7 and 35 substantially in a line with the adjacent end edge of the door. The upper end of the pull arm is bifurcated to receive the ear 6, as will be readily understood. The lower end of the pull arm 17 passes through a 40 sleeve 19 at the floor line, which sleeve protects the arm from damage and the lower end of the arm below the floor is pivotally connected to the top edge of an elongated counter weight body 20, adjacent one end 45 of the body as shown. The counter weight body extends substantially parallel with the face of the furnace, and at its inner end, which end tapers slightly as shown, is pivotally connected to the hanger bracket 21 50 which is secured against the under side of the floor 2.

Extending at right angles to the face of the furnace beneath the floor 2 and across the central portion of the counter weight 55 body 20 is a lever arm 22, the inner end of

which engages the knife edge 23 at the top of the counter weight body, while the outer end of the lever arm is pivotally secured as indicated at 24 to the under side of the floor. Intermediate its ends, the lever arm has 60 mounted thereon a saddle 25 from which there projects upwardly a button 26, the button extending through the floor 2 with the top end thereof projecting a slight distance above the surface of the floor as shown 65 in Figure 2.

From the foregoing description it will be readily seen that upon applying pressure to the button 26, the free inner end of the lever arm 22 will be forced downwardly in 70 turn forcing down the outer end of the counter weight body 20 and pulling upon the pull arm 17 to cause the door 4 to swing upon its pivot 7 to a raised position as shown in dotted lines in Figure 1. Throughout its 75 upward movement, the guide finger 11 carried by the door is guided by the flange 13 and thus when the button 26 is released and the door returns to closed position through the action of gravity, the finger 11 will insure the proper return of the door to position. From this it will be readily seen that even though the pivot pin 7 becomes badly worn the door 4 can not fail to be returned to proper position and can not in any 80 way become jammed or swing away from the face of the furnace, owing to the action of the finger 11 coacting with the track flange 13.

Having thus described my invention, what 90 I claim is:

A swinging door structure of the character described, designed to overlie a wall opening, comprising a door body, a relatively large ear projecting upwardly from one upper corner of said door and having an aperture formed therethrough on a line lying inwardly of and parallel with the adjacent end edge of the door, a pivot element extending through said aperture to support the door, a pull arm arranged at an inclination with respect to the said end edge of the door and having one end pivotally connected to said ear in a plane above the pivot and on a line with the adjacent end edge of the door, and a foot operated lever, connected with the other end of said pull arm for the foot control of the door. 100 105

In testimony whereof I affix my signature.
ROBERT T. HORTON.
